UNITED STATES PATENT OFFICE.

MARTIN URBAN, OF FALL RIVER, MASSACHUSETTS.

FIRE-KINDLER.

1,189,509.

Specification of Letters Patent.

Patented July 4, 1916.

Application filed March 25, 1916. Serial No. 86,682.

To all whom it may concern:

Be it known that I, MARTIN URBAN, a subject of the Emperor of Austria-Hungary, residing at Fall River, in the county of 5 Bristol and State of Massachusetts, have invented certain new and useful Improvements in Fire-Kindlers, of which the following is a specification.

This invention relates to certain new and 10 useful improvements in fire kindlers.

The primary object of the invention is to provide a ready means for initially starting ignition in stoves and furnaces by means of vaporized fuel automatically ignited within 15 out endangering persons or property.

A further object of the device is to provide an electrically lighted gaseous fuel burner adapted for positioning within a stove or furnace for initially starting combustion therein and readily removed when such object is accomplished, the device being serviceable in connection with either a gas or liquid fuel supply.

The present invention contemplates a 25 torch member having a burner provided with both a gas and a liquid fuel supply, the burner having distributing plates and positionable within a stove for kindling purposes, the fuel being adapted for lighting 30 by an electric spark when the device is operatively positioned, it being designed to thereafter cut off the supply and remove the device from the stove.

With these general objects in view and 35 others that will appear as the nature of the invention is better understood, the same consists in the novel construction, combination and arrangement of parts hereinafter more fully described, illustrated in the accompanying drawings, and then claimed.

In the drawings forming a part of this application and in which like designating characters refer to corresponding parts throughout the several views:—Figure 1 is 45 a side elevation of the device with the gas supply pipe broken away. Fig. 2 is a top plan view thereof. Fig. 3 is a central longitudinal sectional view through the body portion of the device. Fig. 4 is a transverse 50 sectional view taken upon line IV—IV of Fig. 3. Fig. 5 is a transverse sectional view taken upon line V—V of Fig. 2. Fig. 6 is a sectional view taken upon line VI—VI of Fig. 5. Fig. 7 is a sectional view taken upon 55 line VII—VII of Fig. 6, and, Fig. 8 is a longitudinal sectional view of the electric

wire conduit illustrating the switch mechanism carried thereby.

It being understood that the present arrangement is in the form of a fire kindler 60 consisting broadly of a torch, the same is herein illustrated having a pear-shaped body 10 serviceable as a handle through which a supply pipe 11 is arranged axially thereof and connected by a coupling 12 to 65 a gasolene tank 13 having an air compressing pump 14. The forward end of the pipe 11 is rigidly connected to a burner 15 in the form of a three-tined fork, the tines or arms 16 of which are provided with forwardly 70 inclined outlets or perforations 17 at opposite sides of distributing plates 18 carried in parallelism upon the lower sides of the said arms.

Controlling valves 19 and 20 are provided 75 for regulating the supply of gasolene to the burner 15 from the tank 13 while forwardly of said valves there is arranged a gas inlet 21 controlled by a valve 22 and supplied with a combustible gas by means of a flexible hose 23. A laterally projecting foot 24 is carried by the body 10 upon which foot and the free edges 25 of the plates 18 the device is adapted to rest.

A chamber 26 is arranged in the body 10 85 provided with a normally closed door 27 while a battery 28 is positioned within the chamber 26 which latter may also accommodate a spark coil not shown, if found desirable. A tubular conduit 29 extends through 90 the side wall of the body 10 communicating with the chamber 26 and has its free end provided with a tubular nipple 30. Two circuit wires 31 are attached to the opposite poles of the battery 28 and extend inwardly 95 of the conduit 29 and are secured to oppositely arranged contact screws 32 positioned therein. A switch collar 33 formed of dielectric material is slidably arranged within the conduit 29 having an operating lug or 100 finger hold 34 projecting through a side slot 35 of the conduit. Opposite contact springs 36 are carried by the collar 33 adapted to close electrical connections between the contact screws 32 and similar 105 screws 37 carried by the said collar and having similar circuit wires 38 attached thereto at their inner ends. The outer ends 39 of the said contact wires 38 extend through the nipple 30 and are slightly 110 spaced apart adjacent the central one of the said distributing plates 18, being designed

for providing a jump spark to ignite the combustion fluid which passes through the burner perforations 17.

The complete operation of the device will 5 be apparent from this detailed description thereof, it being understood that when gas is to be employed for furnishing the flame from the hose 23 and inlet 21, the valve 22 will be opened for allowing the gas to pass 10 through the burner arm 16 and out of the perforations 17 adjacent the opposite faces of the plates 18. At such times, the gasoline valve 20 will be closed and the burner 15 will be arranged within the stove or furnace 15 adjacent and preferably in contact with the combustible material which it is desired to fire. At such times, the switch member shown in Fig. 8 being in its open position, the same will then be closed by means of the 20 lug 34 for shifting the collar 33 to the position therein illustrated, thus connecting the electrical circuit from the battery 28 with the terminal points 39 for inducing an electric spark between such terminals and igniting 25 the gas thereby. As soon as the burner 15 is lighted, the electric switch may be turned off and when the kindling material is sufficiently ignited, the gas valve 22 is closed and the entire device with the burner 15 removed 30 from the stove. When desired to employ the gasoline from the tank 13 as a burning fluid, the pressure upon the gasoline is supplied by means of the pump 14 in the usual manner and the gas valve 22 being 35 closed, the gasoline valves 19 and 20 will be opened, whereupon the gasoline will pass through the burner perforations 17 upon the distributing plates 18 and will be ignited with more or less of a flash by means of the 40 terminals 39 upon closing the electrical switch collar 33. When not in use, the entire device may be positioned upright upon a base 40 carried by the bottom of the gasoline tank 13.

45 It will thus be seen that a serviceable fire igniter is arranged which may be employed for initially starting a blaze in a stove or furnace by means of gasoline or gas without the employment of matches and in a manner 50 to prevent injury to the operator of the device.

While the form of the invention herein shown and described is what is believed to be the preferred embodiment thereof, it is 55 nevertheless to be understood that various

forms, modifications and arrangements of the parts may be made without departing from the spirit and scope of the invention as claimed.

What I claim as new is:—

1. A fire kindler comprising a handle portion, a fork-shaped burner carried by the said handle and having spaced rows of forwardly inclined outlet perforations upon corresponding sides of the arms thereof, distributing plates carried by the said arms between the perforations thereof and arranged in parallelism, and fuel supply members for the said burner.

2. A fire kindler comprising a handle portion, a fork-shaped burner carried by the said handle and having spaced rows of forwardly inclined outlet perforations upon corresponding sides of the arms thereof, distributing plates carried by the said arms between the perforations thereof and arranged in parallelism, fuel supply members for the said burner, a laterally-extending mounting foot carried by the said handle, controlling means for the said fuel supply members, and igniting means arranged adjacent the said plates.

3. A fire kindler comprising a handle, a supply pipe positioned therethrough, controlling valves in the said pipe, a gasoline pressure tank attached to the said pipe, a fork-shaped burner communicating with the said pipe and having three parallel arms each provided with longitudinally-positioned spaced rows of forwardly inclined outlet perforations, and a distributing plate carried by each arm attached thereto between the rows of the perforations therein.

4. A fire kindler comprising a handle, a supply pipe positioned therethrough, controlling valves in the said pipe, a gasoline pressure tank attached to the said pipe, a fork-shaped burner communicating with the said pipe and having three parallel arms each provided with longitudinally-positioned spaced rows of forwardly inclined outlet perforations, a distributing plate carried by each arm attached thereto between the rows of the perforations therein, the said plates being arranged in parallelism, and a gas supply inlet connected to the said pipe intermediate the said handle and burner.

In testimony whereof I affix my signature.

MARTIN URBAN.
